CLAIM

The ornamental design for a buckle, as shown and described.

DESCRIPTION

FIG. 1 is a top plan view of a buckle showing my new design;

FIG. 2 is a front elevational view thereof with the rear elevational view being identical thereto;

FIG. 3 is a left side elevational view thereof;

FIG. 4 is a right side elevational view thereof;

FIG. 5 is a bottom plan view thereof;

FIG. 6 is a top plan view of a buckle showing a second embodiment of my new design;

FIG. 7 is a front elevational view of FIG. 6, the opposite side being identical;

FIG. 8 is a left side elevational view of FIG. 6;

FIG. 9 is a right side elevational view of FIG. 6; and,

FIG. 10 is a bottom plan view of FIG. 6.
